UNITED STATES PATENT OFFICE.

HENRY MALM, OF NEW YORK, N. Y.

PROPELLER.

Application filed September 13, 1926. Serial No. 135,032.

This invention relates to propellers for marine or other uses and comprises two or more blades extending radially from the hub portion of the propeller; and the object of 5 the invention is to provide a propeller of the class specified, the separate blades of which are provided at their inner or hub ends with projecting dove-tailed portions which flare outwardly from a shoulder portion adjacent said end of the propeller, and further to the provision of a plurality of teeth or projections spaced circumferentially on the beveled face of the projecting dove-tailed member and occupying only a portion 10 of the area of said beveled face; a further object being to provide a hub portion composed of separate parts divided transversely of the axis of the hub, said parts having on their adjacent faces when secured together, 15 dove-tailed recesses forming a socket within and between said parts to receive the dove-tailed projecting members of the respective propeller blades; a further object being to provide the recesses in the separate parts of 20 the hub portion with annular grooves to receive the teeth or projections cooperating with the teeth or projections of said dove-tailed projections to lock the propeller blades against rotation when in a given position of adjustment when the separate parts 25 of the hub portion are secured together, it being understood that the interlocking teeth or projections on the hub portion and blade members are of such construction as to permit of the rotary adjustment of the propeller blades in the hub portion to regulate the 30 pitch of the blades in different uses thereof; a further object being to provide a propeller construction of the class specified in which 35 comparatively wide plain bearing faces are provided between the dove-tailed projections and the sockets of the hub portion to securely retain the parts against displacement and to hold the shoulder portions of the propeller blades in firm engagement with the 40 flat outer faces of the hub portion.

The invention shown and described herein is an improvement on that shown and described in a prior application filed by me 45 April 24, 1926, and bearing Serial No. 104,331, and is fully disclosed in the following specification, of which the accompanying drawing forms a part, in which the separate parts of my improvement are designated

by suitable reference characters in each of 55 the views, and in which:—

Fig. 1 is a plan view of a propeller made according to my invention.

Fig. 2 is a partial section on the line 2—2 of Fig. 1.

Fig. 3 is a plan view of one part of a hub portion which I employ; and,

Fig. 4 is an enlarged detail view of the inner end portion of one of the propeller blades employed.

In Fig. 1 of the drawing, I have indicated a propeller consisting of three blade members 5, each of which are of the same construction, and at 6 I have shown the hub portion of the propeller in connection with 70 which the blades 5 are mounted. The hub portion 6 is composed of two parts 7 and 8 which are substantially of the same construction, each part having a bore 9 extending centrally therethrough to receive an engine 75 or other bearing shaft in connection with which the propeller is to be mounted. The adjacent faces of the parts 7 and 8 are provided with three dove-tailed recesses 10 which open outwardly through flat faces 11 80 on the periphery of the separate parts 7 and 8 as clearly seen in Fig. 3 of the drawing. The recesses 10 of one part 7 register with the recesses 10 of the other part 8 when the 85 separate parts are secured together by screws 12 passed through the part 7 and in threaded engagement with the part 8 as seen at 13.

The recesses 10 are each provided substantially centrally thereof with annular grooves 14 in which are formed a series of teeth or 90 projections 15 adapted to cooperate with similar teeth or projections 16 extending circumferentially around the beveled face 17 of a dove-tailed projection 18 at the inner or hub end portions of the blades 5. It will 95 be noted that the teeth or projections 16 enter the grooves 14 and mesh with the teeth or projections 15 in said grooves to provide means for keying or locking the blade members 5 against rotation in the sockets 10 of 100 the hub portion and yet permit of rotary displacement of the blade members 5 with relation to the hub portion.

The comparatively wide surfaces 17^a of the beveled face 17 disposed at opposite 105 sides of the teeth or projections 16, and cooperating with similar surfaces 10^a in the recesses 10 provide strong and durable bear-

ing surfaces between said parts and also reduce the wear on such surfaces.

It will also be understood that in securing the blades 5 to the hub portion 6, the 5 screws or bolts 12 serve to draw the blade members 5 inwardly with relation to the axis of the hub portion in the cooperation of the beveled faces of the recesses 10 and projections 18 to bring the shoulders 18 of 10 the blade members 5 into firm engagement with the flat outer faces 11 of the hub portion, a slight clearance being provided between the abutting faces of the parts 7 and 8 of the hub portion for this purpose as 15 seen at 19 in Fig. 2 of the drawing. If any looseness of the blades 5 should take place due to wear, this looseness may be taken up by tightening the screws 12. However, the only wear which would take place would be 20 that due to adjustments of the parts, which would be very slight.

It will be understood that while I have shown and described one method of carrying my invention into effect, that I am not necessarily limited to the specific structure herein shown and described, and various changes therein and modifications thereof may be made within the scope of the appended claims without departing from the 30 spirit of my invention or sacrificing its advantages.

Having fully described my invention, what I claim as new and desire to secure by Letters Patent, is:—

1. In a propeller, a hub portion divided transversely of the axis thereof to form two independent parts, said parts having on adjacent faces and arranged about the periphery of said hub portion, dove-tailed recesses, 40 portions of the beveled faces of said recesses being grooved, and teeth or projections in the grooved portions of said recesses.

2. In a propeller, a hub portion divided transversely of the axis thereof to form two independent parts, said parts having on adjacent faces and arranged about the periphery of said hub portion, dove-tailed recesses, portions of the beveled faces of said recesses being grooved and teeth or projections in the grooved portions of said recesses, and propeller blades having dove-tailed projections adapted to be mounted in the recesses of said parts, the beveled faces of said dove-tailed projections having circumferentially 50 spaced teeth or projections adapted to enter the grooves in the walls of said recesses, and cooperating with the teeth or projections therein whereby when the separate parts of the hub portion are secured together, said 55 propeller blades are retained against displacement.

3. In a propeller, a hub portion divided transversely of the axis thereof to form two independent parts, said parts having on adjacent faces and arranged about the periph-

ery of said hub portion, dove-tailed recesses, portions of the beveled faces of said recesses being grooved and teeth or projections in the grooved portions of said recesses, propeller blades having dove-tailed projections 70 adapted to be mounted in the recesses of said parts, the beveled faces of said dove-tailed projections having circumferentially spaced teeth or projections adapted to enter the grooves in the walls of said recesses, and cooperating with the teeth or projections therein whereby when the separate parts of the hub portion are secured together, said propeller blades are retained against displacement, and said propeller blades having flat shoulder portions adjacent the dove-tailed projections and the hub portion, and flat outer surfaces in connection with which the shoulder portions operate.

4. A propeller of the class described, the blades of which are provided at the hub end portions thereof with projecting dove-tailed members on a part of the beveled faces of which are arranged gear surfaces, the hub portion of the propeller being fashioned from independent parts between the adjacent faces of which are formed dove-tailed sockets to receive the dove-tailed members of the propeller blades, and the beveled faces of the sockets having annular grooves to receive the gear surfaces on said projecting members, and means in the grooved portions of the hub portion for engaging a predetermined number of the teeth of the gear surfaces to prevent rotation of the blade 100 members in the hub portion when the separate parts are secured together.

5. A propeller of the class described, the blades of which are provided at the hub end portions thereof with projecting dove-tailed members on a part of the beveled faces of which are arranged gear surfaces, the hub portion of the propeller being fashioned from independent parts between the adjacent faces of which are formed dove-tailed sockets to receive the dove-tailed members of the propeller blades, and the beveled faces of the sockets having annular grooves to receive the gear surfaces on said projecting members, means in the grooved portions of the hub portion for engaging a predetermined number of the teeth of the gear surfaces to prevent rotation of the blade members in the hub portion when the separate parts are secured together, and said propeller blades and hub portion having cooperating flat surfaces adapted to be brought into firm engagement by said dove-tailed members in securing the separate parts 110 of the hub portion together.

6. A propeller of the class described, the blades of which are provided at the hub end portions thereof with projecting dove-tailed members on a part of the beveled faces of which are arranged gear surfaces, the hub 120

- portion of the propeller being fashioned from independent parts between the adjacent faces of which are formed dove-tailed members 5 sockets to receive the dove-tailed members of the propeller blades, and the beveled faces of the sockets having annular grooves to receive the gear surfaces on said projecting members, means in the grooved portions of the hub portion for engaging a predetermined number of the teeth of the gear surfaces to prevent rotation of the blade members in the hub portion when the separate parts are secured together, said propeller 10 blades and hub portion having cooperating flat surfaces adapted to be brought into firm engagement by said dove-tailed members in securing the separate parts of the hub portion together, and the adjacent faces of the separate parts of the hub portion being in spaced relation when the several parts of the propeller are assembled.
7. A propeller of the class described, the blades of which are provided at the hub end portion thereof with projecting members, the outer ends of which with respect to the central part of the blades are of greater diameter than the inner end portions, said members having circumferentially spaced projections, the hub portion of the propeller 25 being fashioned from independent parts between the adjacent faces of which are formed sockets of a contour to snugly receive the projecting members of said blades, and said
- sockets having grooves to receive the projections on said members, and means in the grooved portions of said hub for engaging a predetermined number of said projections to prevent rotation of the blades in the hub portion when the separate parts are secured together. 35
8. A propeller of the class described, the blades of which are provided at the hub end portion thereof with projecting members, the outer ends of which with respect to the central part of the blades are of greater diameter than the inner end portions, said members having circumferentially spaced projections, the hub portion of the propeller 40 being fashioned from independent parts between the adjacent faces of which are formed sockets of a contour to snugly receive the projecting members of said blades, and said sockets having grooves to receive the projections on said members, means in the grooved portions of said hub for engaging a predetermined number of said projections to prevent rotation of the blades in the hub portion when the separate parts are secured together, and said propeller blades and hub portion having cooperating flat surfaces 45 adapted to be brought into firm engagement in securing the blades to the hub portion. 50
- In testimony that I claim the foregoing as my invention I have signed my name this 9th day of September, 1926.
- HENRY MALM.
